PICTURE TELEGRAPHY

Johannes Herrmann, Berlin-Siemensstadt, Germany, assignor to Siemens & Halske, Aktiengesellschaft, Siemensstadt, near Berlin, Germany, a corporation of Germany

Application July 12, 1932, Serial No. 622,045
In Germany July 13, 1931

6 Claims. (Cl. 178—6)

The invention is concerned with improvements upon a method used for picture-telegraphy in which the various shadings or densities of a picture are converted into normal telegraphic signals or impulses, the constituent shading values being recorded upon perforated tapes customary in telegraphic apparatus in such a way that the number or position of the holes of a transverse row of the tape results in the shade or brightness of a picture unit or point. For each scanned picture unit a cross-row on the tape and thus, in the transmission of the picture, production of an impulse for each picture point is required. The said perforated strip is then passed through a telegraph transmitter and may be transmitted through any desired telegraphing channel. At the receiving station the incoming perforated strip serves directly for the control of a pencil of light whereby the transmitted picture is re-created photographically.

Methods are known in the prior art in which the carrier wave modulated by the picture currents, after rectification, are fed through a commutator in definite sequence to a number of polarized relays which in accordance to the various shadings are adjusted to different intensities of current. These relays operate the corresponding perforator magnets.

Arrangements of this kind involve the disadvantage that they require a good deal of equipment in the line of sensitive relays and they require a photo cell amplifier insuring a large output power inasmuch as the entire energy required for the actuation of the equipment must be supplied by this amplifier. Hence, the photo cell currents influence directly all of the relays of the means used to produce the perforated paper strip.

The invention obviates these drawbacks by utilizing the amplified photo cell currents only immediately for the conversion of shade values of a picture into telegraphic impulses. The subdivision of the shading according to a dual system (powers of two) makes it possible at the same time to get along with a minimum number of relays.

The photo cell currents in a compensating circuit scheme serve only meditately for the control of the conversion relays, the energy required by the latter being furnished from a local source of current. The power demanded of the photo cell amplifier as a result is decreased to not more than one-tenth of the energy so far required. The photo-electric current modulated by the shading values or densities of the picture, in a

bridge arrangement, is compared with a non-modulated photo-electric current adjusted in accordance with the desired number of shading values and being, for instance, variable by stages. The standard circuit contains a series connection of resistances graduated according to dual numbers. The said resistance is cut in circuit or short-circuited by the agency of a polarized relay included in a local circuit and keyed by a cam contact disk. According to whether the modulated current is larger or smaller than the non-modulated current a polarized relay connected in the zero arm of the bridge will be correspondingly operated. As a result the circuit of the relays which serve to cut in the resistances will be acted upon and thus selection of the magnets for perforating the strip is insured.

The compensating current, as previously pointed out, is preferably derived from the photo cell amplifier in order that an absolute zero for the shade or density scale may be obtained. But if this is dispensed with a local source of supply may be employed.

Fig. 1 shows an embodiment of the invention by way of example for an arrangement adapted to convert 15 density values. In order that a subdivision of a density scale containing 15 gradations by the dual system may be obtained, the four elements 1, 2, 4, and 8 are required, in other words, fundamentally speaking, the four-unit code will be sufficient. With the said elements it is feasible to represent all of the values between 1 and 15.

The photo-cell amplifier V furnishes the carrier frequency f_1 and the modulated carrier and sidebands f_2 . These frequencies are separated by the filters f_1, f_2 where f_1 is simply a very sharply tuned resonant circuit so as to select only the carrier frequency, whereas f_2 is a band-pass filter whose mid-frequency coincides with the carrier frequency and whose band width is wide enough to pass all the generated side-bands. The output of the filter f_2 is fed to the full wave rectifier G_2 . The output of the filter f_1 is fed to a rectifier G_1 through an automatically variable attenuator. The outputs of the two rectifiers G_1 and G_2 are then compared in a circuit which includes the vacuum tube E. The voltage fed to the rectifier G_1 will depend on the armature positions of the relays A, B, C, D. If these armatures are in the position I, it will be observed that the output of f_1 is short circuited. It is only when the armatures are in position II that voltage will be fed to this rectifier.

To illustrate the operation of this invention,

assume that a density value of 11 is furnished by the output of the photo-cell amplifier V. The sequence of operation is then as follows. Cam n_{11} closes the armature n_{11} . All of the armatures 5 of the relays A, B, C, D are in position I. Consequently in this condition the output of the rectifier G_2 drives the grid of the tube E negative so that plate current does not flow through this tube to operate the relay R, keeping the armature r in position I. Cam n_1 then closes to operate the relay A to pull its armature a into position II. With the relay in this position, a voltage of density value 8 is supplied to the rectifier G_1 because the resistor R_8 is now placed in the circuit. 10 Since the value of the output of the rectifier G_1 is still less than the output of the rectifier G_2 , the tube E still has its grid held at a negative potential, so that the armature r is still held in position I. The cam n_2 then closes, but inasmuch 15 as the armature r is held in position I, the polarity of the battery is such as to keep the armature a in position II. Cam n_3 then closes and four more units of voltage are added to the rectifier G_1 . The sum of the voltages now acting on the 20 rectifier G_1 is 12, which is greater than the density value 11, and so the grid of the tube E is made positive. This permits current to flow through the relay R to pull the armature r to position II. Cam n_4 then closes and the polarity of the battery is now such as to pull the armature b back to position I. This shorts out the resistance R_4 . Cam n_5 then closes the armature n_5 and the sum 25 of the voltages acting on the rectifier is now 10 units. This makes the grid of tube E negative so that the relay R operates to pull the armature r to position I. Cam n_6 then closes, but the polarity of the current flowing through the relay coils of C continues to hold the armature c in position II. Cam n_7 then closes armature n_7 and 30 adds another unit of voltage to give complete balance. The closure of the armature n_8 continues to hold the armature d in position II. In this condition then the voltage of the unmodulated frequency is equal to that of the modulated 35 frequency. Cam n_9 then operates to close armature n_9 and the perforating magnets M_1 , M_2 and M_3 receive current through the connections of the armatures a , c , d , which are in position II. The perforating magnet M_4 is unaffected since 40 the armature b is in such a position that it does not complete the circuit back to the actuating voltage. Cam n_{10} then operates to close armature n_{10} which immediately restores all the armatures a , b , c , and d back to position I and the 45 process is then ready to be repeated for the next density value.

Having now described my invention, what I claim and desire to secure by Letters Patent is the following:

1. In a picture telegraph apparatus wherein picture signals are to be transmitted as a perforated record, the method of preparing the record which comprises the steps of developing carrier wave energy, developing picture signal energy, modulating the developed carrier wave in accordance with the developed picture signal energy, comparing the developed carrier and the modulated carrier energies with each other, altering the resistance characteristic of an elec-

trical circuit in accordance with the difference between the compared energies and perforating a record member in accordance with the altered resistance characteristic of the electrical circuit.

2. In a picture telegraph apparatus wherein picture signals are to be transmitted as a perforated record, the method of preparing the record which comprises the steps of developing carrier wave energy, developing picture signal energy, modulating the developed carrier wave in accordance with the developed picture signal energy, comparing the developed and the modulated carrier energies with each other a plurality of times during a predetermined unit time period, altering for each comparison the resistance characteristic of an electrical circuit in accordance with the electrical difference produced by the comparison, and perforating a record member in accordance with the altered resistance characteristic of the electrical circuit.

3. In picture telegraph apparatus wherein picture signals are transmitted from a perforated tape, the combination which comprises a plurality of relays, means for producing picture modulated photoelectric currents, means for producing non-modulated photoelectric currents, means for comparing the modulated current with the non-modulated current, a plurality of resistance elements sub-divided according to the powers of 2 associated with the relays, said relays serving to control the resistance elements, a polarized relay operated in accordance with the comparison of the two photoelectric currents, means controlled by the polarized relay to cause the plurality of relays to cut-in circuit or short circuit the individual resistance elements, and perforating magnets controlled in accordance with the resistance values cut-in circuit and short circuited to control the perforations representative of the picture subject upon the message tape.

4. In picture telegraph apparatus wherein picture signals are transmitted from a perforated tape, the combination which comprises a plurality of relays, means for producing picture modulated photoelectric currents, means for producing non-modulated photoelectric currents, a bridge circuit for comparing the modulated current with the non-modulated current, a plurality of resistance elements subdivided according to powers of two associated with the relays, said relays serving to control the resistance elements, a polarized relay operated in accordance with a comparison of the two photoelectric currents, means controlled by the polarized relay to cause the plurality of relays to cut-in circuit or short circuit the individual resistance elements, and perforating magnets controlled in accordance with the resistance values cut-in circuit and short circuited to control the perforations representative of the picture subject upon the message tape.

5. The system claimed in claim 3 comprising in addition a local circuit for energizing the perforating magnets.

6. The system claimed in claim 3 comprising in addition cam contacts for controlling the operation of the conversion relays and perforator magnets.

JOHANNES HERRMANN.
